UNITED STATES PATENT OFFICE.

EDWARD J. HUNT, OF WEST ORANGE, NEW JERSEY.

ADVERTISING LAMP AND RADIOMETER.

1,290,749.

Specification of Letters Patent.

Patented Jan. 7, 1919.

Application filed November 8, 1917. Serial No. 200,967.

To all whom it may concern:

Be it known that I, EDWARD J. HUNT, a citizen of the United States, residing at Llewellyn Park, West Orange, in the county 5 of Essex and State of New Jersey, have invented certain new and useful Improvements in Advertising Lamps and Radiometers, of which the following is a specification.

10 This invention relates to a motor device operating on the principle of the radiometer in which the moving or motor elements are caused to rotate upon their axes by the action of light.

15 The purpose of my invention is to provide a device which may be inserted within the inclosure of an ordinary incandescent lamp bulb and be combined with the filament support in a manner permitting the use of the

20 usual lamp filament so that the light issuing therefrom shall cause the rotation of the several motor vanes. The apparatus is mainly useful for advertising purposes where it is desired to attract attention by

25 means of moving objects. It is especially adapted for window or show case displays which are lighted at night, the apparatus serving as a source of light as well as a device to attract attention.

30 In the accompanying drawings Figure 1 is a side elevation of an apparatus embodying my invention; and Fig. 2 is a central cross sectional view through one of the sets of motor vanes.

35 The container may be in the form of the ordinary well-known incandescent electric lamp bulb, all of the parts being inclosed in the glass bulb 1, which must be exhausted and contain only rarefied air or gas.

40 The motor elements consist of a series of vanes 3, preferably four or more, which are silvered upon one side and blackened upon the other side, as by being covered with carbon, such as lamp black, and carried by a 45 central stem or shaft 4, rotatably mounted

in a yoke or support 6. These yoke supports are preferably made of glass and are attached to or a part of the stem 8 which supports the lamp filament 9.

50 I have illustrated three motor devices, but it is evident that any convenient number may be employed and that they may be

placed at various angles with respect to the filament, not only for design purposes, but also for the purpose of causing different amounts of light to reach the several sets of 55 motor vanes. As is well understood, the light falling upon the sides of the vanes covered with carbon is absorbed while that falling upon the opposite silvered sides is 60 reflected and the reaction caused by the latter light rays results in the rotation of the sets of motor vanes about their axes. By varying the distance and angular relation of the several sets, different speeds result and 65 thereby produce varying effects.

In the day time this device may be used as an ordinary radiometer, the vane wheels being rotated by the sunlight, while at night the vanes are actuated solely by the interior 70 light rays emanating from the filament.

I have shown only one form of the apparatus, but it is evident that various structural changes and modifications may be made within the scope of my claims without 75 departing from my invention.

I claim:

1. An apparatus of the class described, comprising a transparent sealed bulb or vessel containing a rarefied gas, a support within said vessel, sets of radiometer vanes carried by axles rotarily mounted upon said support, and a lamp filament carried by said support and having terminal connections mounted upon the outer wall of said vessel. 80 85

2. An apparatus of the class described, comprising an incandescent lamp containing a rarefied or inert gas and provided with the usual filament adapted to become incandescent upon the flow of electric current there-through, and a set of radiometer vanes rotarily mounted within the bulb of the lamp in a position to be affected by the light rays emanating from the filament, whereby the vanes will be caused to rotate about their 90 95 supporting axle whenever the lamp is lighted.

In testimony whereof I affix my signature in the presence of two witnesses.

EDWARD J. HUNT.
